UNITED STATES PATENT OFFICE.

SAMUEL KETCHUM, OF HOBOKEN, NEW JERSEY, ASSIGNOR TO M. H. TREADWELL COMPANY,
A CORPORATION OF NEW YORK.

DUMPING-CAR.

No. 909,307.

Specification of Letters Patent.

Patented Jan. 12, 1909.

Application filed March 4, 1908. Serial No. 419,085.

To all whom it may concern:

Be it known that I, SAMUEL KETCHUM, a citizen of the United States, residing at Hoboken, in the county of Hudson and State 5 of New Jersey, have invented certain new and useful Improvements in Dumping-Cars, of which the following is a full, clear, and exact specification.

This invention relates to dumping cars, 10 and has particular reference to cinder cars or the like wherein a tilting and bodily movable car body is mounted to be dumped in opposite directions from a central upright position, as may be desired.

15 More particularly, the invention comprises a power actuated dumping car having an actuating cylinder and piston and has especial reference to the provision of means whereby the momentum of the car body at 20 the end of the outward stroke is automatically opposed by the actuating pressure, whereby the movement is checked without straining the apparatus.

A particular object of the invention is to 25 provide means controlled by the movement of the motor whereby the actuating pressure may be admitted to check the movement at any predetermined portion of the stroke, and thus permit the total checking pressure at 30 the end of the stroke to exceed the actuating pressure to any desired extent.

As herein exemplified, the invention is carried out by connections between the motor cylinder and an automatic valve having 35 actuating connection with the movable part of the motor such that the valve is capable of manual actuation to start the movement by admitting pressure on one side of the piston and is automatically actuated by 40 the movement of the motor at a predetermined point to admit pressure to the other side of the piston for the purpose of checking the movement of the car body at the end.

The invention will be more fully understood 45 in connection with the description of the accompanying drawings, wherein—

Figure 1 represents an end view of a dump car embodying the invention, and Fig. 2 is a detail view on an enlarged scale showing the 50 connections between the motor and the automatic controlling valve.

The car frame comprises the usual under frame carried by end bolsters 1, the under frame not being herein shown, and is sup-

ported at the ends on trucks, which will not 55 be particularly described herein, as these may be arranged according to particular necessities. The bolsters 1 each have a stationary rack 2 and a track 3, and the car body 4 is preferably secured to a bail 5 60 which is provided with trunnions 6 at diametrical points. Rigidly secured to the trunnions 6 are gears 7 adapted to mesh with the racks 2 (at each end of the car body) and rollers 8 which roll on the tracks 3, the parts 65 thus far described being of a well known construction.

In order to actuate the car body, a movable cylinder 9 having a fixed piston 10 and a hollow piston rod 11 is provided, the cylinder 70 having a box at each end and a removable key 12 which may be used to fasten the trunnion box 13 at each end of the cylinder according to the side on which the car body is to be dumped. The cylinder 9 slides on 75 guides 14 carried by the end bolsters 1, and fluid pressure is supplied to one or the other side of the piston through the hollow piston rod 11 by pipes 15, 16. The pipes 15, 16 are connected with the valve cylinder 17, which 80 latter is also connected with a source of supply 18 and an exhaust 19. Mounted within the valve casing 17 is a double piston 20 carried by an actuating rod 21, the pistons being so spaced as to simultaneously close the pipes 85 15, 16 when the car body is at rest. When the piston 20 is thrown so as to connect the pipes 18 and 15, pressure will be admitted to the right side of piston 10 through the hollow piston rod, and the cylinder 9 will move to 90 the right, carrying the car body with it in case the parts are in the position shown in Fig. 1. When the valve rod 21 is thrown to the left in Fig. 2, the pressure will be admitted on the left side of the fixed piston 10, 95 which would throw the car body outward to the left in case the cylinder 9 was positioned at the other end of its stroke, by unlocking the connection between the cylinder and trunnion by means of the key 12. It should 100 be understood that in both cases, when the supply is open to one side of the piston, the other side is open to the exhaust.

In order to actuate the piston rod 21, a hand lever 22 and ratchet segment 23 with 105 a latch 24 is provided, and the lever 22 is connected with the piston rod 21 through a link 25, which latter is pivoted to a link 26. The

link 26 is itself attached to the moving part of the motor, in this case the cylinder 9 by another link 27.

In order to tilt the car body to the right, 5 the lever 22 will be thrown to the right, which will throw the valve 20 in the same direction so as to connect pipes 18 and 15 and 16 and 19, admitting pressure on the right of piston 10 and starting the car body. The ratchet 10 23 enables the lever 22 to be set at any desired position, for a purpose which will now be explained. As the cylinder 9 moves to the right, it will commence to throw the valve 20 to the left, cutting off the connection 15 between pipes 18 and 15, and consequently the supply pressure from the actuating side of the cylinder. The point at which this cut-off occurs will be determined by the extent to which the lever 22 was thrown, so 20 that by this means an automatic cut-off is provided which can be graduated to take place at any desired portion of the stroke. The movement of the car body does not cease upon the cutting off of the pressure, 25 and it will continue moving by its own momentum, and the object of this invention is to utilize this further movement due to the momentum of the car body to admit actuating pressure to the other side of the motor 30 piston and thus check the car body by means of the actuating pressure. This will be accomplished by the continued movement of the automatic valve 20 as the car body moves so that after the connection between 35 pipes 18 and 15 is cut off, further movement will make a connection between pipes 18 and 16, thus admitting the pressure to the exhaust side to check the movement, and opening the other side of the piston 10 40 to the exhaust through pipes 15 and 19.

It will be seen that the movement of the valve 20 will be proportional to the movement of the motor while the motor is moving, but that the valve 20 can be manually operated 45 independently of the motor to an extent varying according to the point at which the cut-off of actuating pressure and the admission of checking pressure is to take place.

In order to maintain a checking pressure 50 higher than the actuating pressure, the passage of checking pressure back through pipes 16 and 18 is prevented by an automatic valve 29 located in pipe 18, which valve opens to admit pressure, such as steam or 55 air, but closes when the cylinder pressure exceeds the supply pressure. It is thus possible to secure a checking pressure much in excess of actuating pressure by means entirely automatic after the lever 22 has once 60 been set and latched. Also, it will be seen that the checking pressure will depend upon the time of cut-off, as the sooner the checking pressure is admitted the greater volume of fluid there will be to be compressed by the

further movement of the car body due to its own momentum.

While the invention is shown herein applied to a motor wherein the piston is fixed and the cylinder movable, it will be obvious that the invention may be carried out with other forms of motors where the piston moves and the cylinder remains stationary, it only being essential to connect the controlling valve with some moving part of the motor, whether cylinder or piston being immaterial. It will also be seen that when the trunnion and the movable part of the motor are disconnected by removing the key, for the purpose of reversing the operation of the car body from one side to the other, that the automatic valve will act in the same manner, but under such circumstances the positioning of it will be somewhat different than for tilting a loaded car body. In practice, the operator will very quickly learn the proper 85 positions of the lever 22 for the various conditions of operation.

Modifications and changes in the specific apparatus herein described may be made without departing from the scope of the 90 invention.

Having thus described my invention, I declare that what I claim as new and desire to secure by Letters Patent, is:

1. In a dumping car, the combination 95 with a dumping car body, and a fluid pressure actuating motor, of means for supplying power to start the motor, means for cutting off the power after the motor has started, means for applying power tending 100 to reverse the motor, and means for confirming the reversing power to secure a high checking pressure.

2. In a dumping car, the combination with a dumping car body, and an actuating 105 motor, of manually controlled means for supplying power to start the motor, means for automatically cutting off the power after the motor has started, and means for automatically supplying power tending to reverse the motor.

3. In a dumping car, the combination with a dumping car body, and an actuating motor, of manually controlled means for supplying power to start the motor, and 115 means actuated by the motor for automatically cutting off the power after the motor has started.

4. In a dumping car, the combination with a dumping car body, and an actuating 120 motor, of manually controlled means for supplying power to start the motor, means for automatically cutting off the power after the motor has started, and means whereby the time of cutting off the power can be 125 varied.

5. In a dumping car, the combination with a dumping car body, and an actuating cylin-

der and piston, of a controlling valve, means for manually operating the valve to start the motor, and connections between the valve and a moving part of the motor whereby to reverse the valve to cut off the power after the motor has started.

6. In a dumping car, the combination with a dumping car body, and an actuating cylinder and piston, of manually controlled means 10 for supplying power to start the motor, and means for automatically cutting off the power after the motor has started and applying power in the reverse direction.

7. In a dumping car, the combination with 15 a dumping car body, and an actuating motor, of manually controlled means for supplying power to start the motor, means for automatically cutting off the power after the motor has started, means for automatically 20 supplying power tending to reverse the motor, and means whereby the reversing power is automatically cut off.

8. In a dumping car, the combination with a dumping car body, and an actuating cylinder and piston, of manually controlled means 25 for supplying pressure to start the motor, means for automatically cutting off the pressure after the motor has started and applying pressure in the reverse direction, and means 30 for confining the reversing pressure so applied whereby to secure checking pressure above actuating pressure.

9. In a dumping car, the combination with an actuating motor, of means for manually 35 admitting power to start the motor, and means actuated by the motor for applying

power to check the motor and timed to act according to the position in which said starting means is set.

10. In a dumping car, the combination 40 with an actuating cylinder and piston, of a controlling valve for admitting fluid pressure to start the motor in either direction, and connections between said motor and said valve whereby the latter is automatically 45 closed by the movement of the motor.

11. In a dumping car, the combination with an actuating cylinder and piston, of a controlling valve for admitting fluid pressure to start the motor in either direction, and 50 connections between said motor and said valve whereby the latter is automatically closed by the movement of the motor and opened on the reverse side.

12. In a dumping car, the combination 55 with an actuating cylinder and piston, of a controlling valve for admitting fluid pressure to start the motor in either direction, and connections between said motor and said valve whereby the latter is automatically 60 closed by the movement of the motor and opened on the reverse side, and means independent of said valve for confining the pressure on said other side to check the movement by the compression of such pressure. 65

In testimony whereof I affix my signature, in presence of two witnesses.

SAMUEL KETCHUM.
